UNITED STATES PATENT OFFICE.

HENRY ILLBACK, OF EAST ORANGE, NEW JERSEY.

RING OR BAND FOR USE IN PILE-DRIVING.

1,220,229.

Specification of Letters Patent. Patented Mar. 27, 1917.

Application filed August 12, 1916. Serial No. 114,508.

To all whom it may concern:

Be it known that I, HENRY ILLBACK, a citizen of the United States, residing at East Orange, in the county of Essex and State of New Jersey, have invented certain new and useful Improvements in Rings or Bands for Use in Pile-Driving; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in rings or bands, such as are used with piles during the operation of driving the piles in position; and, this invention has reference, more particularly, to a novel construction of metal ring or band, for use with piles while driving the same in place, with a view of providing a ring or band which will not break while subjected to the constant blows of the drop or hammer of a pile-driving machine.

It has been found in practice, that with the solid rings or bands now used with piles, during the driving operation, the constant blows from the heavy drop or hammer employed, often breaks or cracks the ring or band, and, furthermore, on account of the great heat produced, the expansion of the metal or of the upper end-portion of the pile, very often results in the splitting or breaking of the rings.

The principal object of the present invention, therefore, is to provide a novel and simply constructed ring or band, adapted to be placed upon the upper end of a pile, which is subject to expansion, and which will not split or break when subjected to the blows from the heavy drop or hammer of the pile-driving machine, during the operation of driving the pile in place.

Other objects of this invention not at this time more particularly enumerated will be clearly understood from the following detailed description of the present invention.

With the various objects of the present invention in view, the said invention consists, essentially, in the novel ring or band for use with piles; and, the invention consists, furthermore in the general arrangements and combinations of the various parts thereof, as well as in the details of the construction of

the same, all of which will be more fully described in the following specification, and then finally embodied in the clauses of the claim which are appended to and which form an essential part of the said specification.

The invention is fully illustrated in the accompanying drawings, in which:

Figure 1 is a top-edge view of a ring or band, certain parts thereof being represented in horizontal section, said view illustrating one embodiment of the principles of the present invention.

Fig. 2 is a side view of the said ring or band; and Fig. 3 is a similar view of the opposite side of the ring or band.

Similar characters of reference are employed in the said above described views to indicate corresponding parts.

Referring now to the said drawings, the reference-character 1 indicates a complete ring or band for the purposes herein-above stated, and made according to and embodying the principles of the present invention.

From an inspection of Fig. 1 of the drawings, it will be seen that the ring or band 1, which may be of any suitable size, both as to its diameter and its width, consists of a plurality of ring-shaped elements, usually two of such elements as 2 and 3 being employed, said elements 2 and 3 being spirally disposed, and having the overlapping end-portions 4, 5, 6 and 7, arranged substantially as shown in said Fig. 1 of the drawings. The said overlapping end-portions are suitably rigidly secured together by means of rivets 8 and 9, or by means of other suitable fastening devices. At a point opposite the said overlapping end-portions, the said ring-shaped elements 2 and 3 have contacting portions, as 10 and 11, said contacting portions being also rigidly secured together by means of a rivet 12, or by means of other suitable fastening means, as will be clearly evident.

The said ring-shaped elements 2 and 3 are of such construction, that when arranged and secured in their assembled relation, the complete ring or band 1 thus provided, will have oppositely disposed open spaces, as 13 and 14, between the said elements 2 and 3, substantially as indicated in Fig. 1 of the drawings.

The herein described ring or band is used with a pile, during the usual operation of driving the pile in place, by placing the ring

or band upon the upper end of the pile, and then subjecting both the ring or band and the end of the pile to a succession of blows from a heavy drop or hammer of a pile-
5 driving machine.

Heretofore, in practice, solid rings or bands have been employed for this purpose, and it has been found that due to the heat created, the expansion of the metal-ring or
10 band would very often crack or split, or such breaking of the ring or band would sometimes be caused by the force due to the compression of the end of the pile.

With the form of ring or band made according to the principles of the present invention, the spaces 13 and 14 between the two ring-shaped elements 2 and 3, readily permit of sufficient expansion of the inner ring-shaped element 3, without any danger
20 of shearing or cutting the rivets 8, 9, or 12, and at the same time overcoming the possibility of the complete ring or band splitting, cracking, or breaking, as heretofore with the employment of the usual solid ring or
25 band.

I claim:—

1. A ring or band for use in the driving of piles, comprising a plurality of ring-like members, one set of end-portions of a pair of
30 said ring-like members being arranged end to end and disposed between the other end-portions of said ring-like members, and means for securing said ring-like members in assembled relation.
- 35 2. A ring or band for use in the driving of piles, comprising a plurality of spirally disposed ring-like members, one set of end-portions of a pair of said ring-like members being arranged end to end and disposed between the other end-portions of said ring-like members.
- 40 3. A ring or band for use in the driving of piles, comprising a plurality of spirally disposed ring-like members one set of end-portions of a pair of said ring-like members being arranged end to end and disposed between the other end-portions of said ring-like members, and means for securing said ring-like members in assembled relation.
- 45 4. A ring or band for use in the driving of piles, comprising a plurality of ring-like members arranged one within the other, means for securing said ring-like members in assembled relation at diametrically opposite portions, said ring or band being formed with open spaces intermediate of the secured portions of said ring-like members.

5. A ring or band for use in the driving of piles, comprising a plurality of spirally disposed ring-like members, arranged one within the other and having overlapping end-portions, means for rigidly securing said overlapping end-portions, said spirally disposed ring-like members being spaced apart so as to provide an open portion for expansion.

6. A ring or band for use in the driving of piles, comprising a plurality of spirally disposed ring-like members, arranged one within the other and having overlapping end-portions, means for rigidly securing said overlapping end-portions, means for rigidly securing said ring-like members at a point diametrically opposite their overlapping end-portions, said ring-like members being spaced apart intermediate of said secured portions so as to provide open spaces for expansion.

7. A ring or band for use in the driving of piles, comprising a plurality of ring-like members arranged one within the other, rivets for securing said ring-like members in assembled relation at diametrically opposite portions, said ring or band being formed with open spaces intermediate of the secured portions of said ring-like members.

8. A ring or band for use in the driving of piles, comprising a plurality of spirally disposed ring-like members, arranged one within the other and having overlapping end-portions, rivets for rigidly securing said overlapping end-portions, said spirally disposed ring-like members being spaced apart so as to provide an open portion for expansion.

9. A ring or band for use in the driving of piles, comprising a plurality of spirally disposed ring-like members, arranged one within the other and having overlapping end-portions, rivets for rigidly securing said overlapping end-portions, a rivet for securing said ring-like members at a point diametrically opposite the said riveted overlapping end-portions, said ring-like members being spaced apart intermediate of said secured portions so as to provide open spaces for expansion.

In testimony that I claim the invention set forth above I have hereunto set my hand this 9th day of August, 1916.

HENRY ILLBACK.
